UNITED STATES PATENT OFFICE.

SAMUEL G. REED, OF NEWTON, MASSACHUSETTS.

BELLOWS.

SPECIFICATION forming part of Letters Patent No. 247,517, dated September 27, 1881.

Application filed February 14, 1881. (Model.)

To all whom it may concern:

Be it known that I, SAMUEL G. REED, of Newton, in the county of Middlesex and State of Massachusetts, have invented a new and 5 useful Improvement in Bellows, of which the following is a specification.

In the accompanying drawings, in which similar letters of reference indicate like parts, Figure 1 is a front elevation of a bellows and 10 operating mechanism embodying my invention. Fig. 2 is a vertical section of the same upon line *x y*, Fig. 1. Fig. 3 is a vertical section, taken at a right angle to that of Fig. 2, of the bellows proper, with the valve raised so as to 15 operate the same. Fig. 4 is a section upon line *z z*, Fig. 1, showing adjacent parts, a portion being represented as broken out, the better to illustrate the invention.

a and *a'* are respectively the upper and lower 20 portions of a double-acting bellows. *b* is the top; *c*, the bottom, provided with the opening *c'*, and *d d* the central partitions or partition having the opening *d'*. *a''* is the outlet or communicating pipe carrying the blast of air to 25 the desired place.

e is a hemispherical or spherical rubber valve secured to the under side of the spring *e'*, mounted upon blocks *e''*. A chain, *f*, extends from the valve *e* to a similar valve, *g*, secured 30 to the top of the rod *h*, which is provided with a rack, *h'*, meshing into cogs upon the wheel *k*, supported by the shaft *k'*. It will be noticed that the cogs upon the wheel *k* are in two sets, opposite each other, the rest of the 35 periphery being plain. *l*' is a guide-rod running in the guides *l l*.

m is a horizontal rod, one end of which is secured to the top *b*, (which is usually weighted,) and the other end to the vertical rod *m'*, which 40 is held by the lever *n*, pivoted to the post *n'*, and runs in the tube *m''*.

v is an unwinding-barrel, and *w* a pulley for accommodating a weight for supplying power.

The operation of my device is as follows: 45 Power of any kind having been applied to the shaft *k'*, the wheel *k*, which is fixed thereupon, turns, and the cogs engage the rack *h'*, raising the rod *h*, (which is guided by means of *l l l'*), and consequently the rubber valve *g*. The 50 raising of the rod *h* and valve *g* slackens the

chain *f*, thus allowing the valve *e* to be raised from the opening *d'* by means of the spring *e'*, as seen in Fig. 3. The valve *g* reaches the opening *c'*, makes a tight fit therein on account of its shape and material, and, pushing up the 55 bottom *c*, forces the air from the lower into the upper chamber, and thence into the pipe *a''*. As the wheel *k* turns and the cogs pass the rack *h'* the plain portion of the wheel is reached, and the rod suddenly drops into the position 60 shown in Fig. 2, straightening the chain and pulling the valve *e* down into the opening *d'* in the partition *d*. The cogs on the opposite side of the wheel then engage the rack, and the operation is repeated. When the rod *h* 65 rises, as above described, and about as its valve *g* reaches the bottom *c*, the projection *n''* lifts the lever *n*, and hence the rods *m'* and *m*, which assist in raising the top *b*, (which is usually weighted,) thus obviating the necessity of the 70 air doing all the work. When the rod *h* drops and the valve *e* closes, the weight of the top *b* presses out the air in the upper chamber into the pipe *a''*. Thus the bellows is rendered 75 double-acting.

Of course two, three, or more bellows may be applied to the shaft *k'*, and their wheels *k* so arranged that one or more will always be sending air into the common pipe, thus securing 80 a steady flow.

In order that a steady friction or labor may be applied to the actuating-wheel, so that it may not jump when the cogs have passed the rack and the plain portion appears, I propose to apply a cam which will compensate for the 85 absence of cogs on certain portions of the wheel. *p* shows a wheel intended to run a bellows, and *s* a cam, both fixed to the shaft *k'*. A weight, *t*, pivoted to the post *t'*, lies upon the cam, which is so placed as to present its projecting portion where there is the greatest radius, and consequently the most friction, at the time when the plain or blank portion of the wheel is presented to the rack, thus producing 90 the desired effect—viz., the equalization of 95 the motion of the wheel *p*.

The valves may be spherical or semi-spherical in shape, and are constructed of rubber or other similar elastic or flexible substance or compound.

Having thus fully described my invention, what I claim, and desire to secure by Letters Patent, is—

1. The combination, with the bellows a a' , provided with openings c d in the bottom c and partition d thereof, of the elastic spherical or semi-spherical valves e g , connected by a chain or cord, f , the spring e' , and the rod h , arranged to operate substantially as and for the purposes set forth.
2. In combination with the bellows a a' , valves and chain e g f , and rod h , provided with rack h' , and lifting-pin n'' , the lever n , and rods m' m , the latter secured to the bellows top b , constructed and arranged substantially as and for the purpose described.
3. In combination with the rack h' , secured to the lifting-rod h , and an actuating-wheel, p , hav-

ing its periphery geared and blank alternately, the cam s and weight or drop t , such friction-cam s being arranged to present its projecting portions to the drop when the wheel presents its blank portions to the rack, substantially as and for the purpose herein specified.

4. In combination with the bellows provided with the opening c' in the bottom c , the perpendicular lifting-rod h , surmounted by a valve, g , and provided with the rack h' , and the gear-wheel k , constructed as described, upon the shaft k' , substantially as and for the purpose set forth.

SAMUEL G. REED.
